HYDRAULIC LOADER OR UNLOADER

Philip W. Soucia, Caribou, Maine

Application January 31, 1944, Serial No. 520,478

7 Claims. (Cl. 212—51)

The invention relates to improvements in loading and unloading apparatus, and more particularly to a novel device for use in loading or unloading a motor truck, or the like.

One of the objects of the invention is to provide a loader or unloader including a hydraulic ram designed for lifting a load either from a platform or the body of a vehicle.

Another object is to furnish a loader including a substantially vertical mast so mounted that it may be turned about its own axis to permit a load to be transferred to or from a platform adjacent the vehicle on which the apparatus is mounted.

A still further object is to supply a loader of the mast and pivoted arm type in which parts are adjustably connected to suit variation in the weights of loads, etc.

With the foregoing objects outlined and with other objects in view which will appear as the description proceeds, the invention consists in the novel features hereinafter described in detail, illustrated in the accompanying drawing, and more particularly pointed out in the appended claims.

The drawing is an elevation of the apparatus, shown mounted on a motor vehicle.

Referring to the drawing, 1 designates a base plate adapted to be rigidly secured by any suitable means, such as bolts 2, to the floor 3, or the like, of the vehicle on which the apparatus is mounted.

A socket or hollow pedestal 4 has its lower end rigidly secured to the base plate and extends upwardly at a slight angle to the vertical, as is clear from the drawing.

A mast 5 has its lower end portion rotatably mounted in the socket, and is provided with a handle 6 to facilitate turning of the mast. An extension 7 is rigidly connected to the top of the mast and is preferably provided with a plurality of holes 8 for the reception of a bolt 9 adjustably employed in pivotally securing the inner end of an arm 10 to the mast. An apertured plate 11, or the like, having a series of holes 12 is rigidly connected to the medial portions of the arm, and is, in turn, pivotally connected by a bolt 13 to the rod 14 of a ram 15. The lower end of the rod has a piston or plunger 16 slidably arranged in a cylinder 17, the lower end of which is pivotally connected at 18 to the mast 5. A pressure fluid, such as oil or water, is introduced into and discharged from the lower end of the cylinder by means of a hose 19, preferably connected to a control valve 20 mounted on the

socket 4, and having a handle 21, convenient to the handle 6 so that both handles may be readily manipulated by an operator positioned in the vehicle. The valve is supplied with a pressure fluid by means of a conduit 22 which may be connected to a pressure pump (not shown) mounted on the same vehicle as the loader or on a tractor which hauls the vehicle.

A chain 23, or the like, is suspended from the outer end of the arm 10 and supports any suitable gripping device 24 adapted to grip the load.

In operation, the valve 20 can be manipulated to lower the tongs 24, or the like, to grip a load on a platform alongside the vehicle, and then the valve may be turned to introduce the pressure fluid into the lower end of the cylinder. Such pressure fluid will force the plunger 16 upwardly and, therefore, cause the arm 10 to swing in a counter-clockwise direction. When the arm is swung upwardly to the proper height, the valve is manipulated to trap the pressure fluid in the cylinder, and then the handle 6 may be turned to cause the mast to transfer the load into the vehicle. Obviously, if the apparatus is employed in unloading the vehicle, this procedure will be reversed.

While the apparatus has been illustrated as mentioned in a truck body near the side of the same, I prefer in some cases to mount it in the middle of the floor of the truck body with the mast inclined toward an end of such body because in that event, if the load is lifted from a platform arranged at one side of the truck body, such load 30 will automatically cause the mast 5 to turn in the socket 4 to shift the load to a position over the truck body without any effort on the part of the operator.

From the foregoing, it is believed the construction, operation, and advantages of the invention may be readily understood, and I am aware that changes may be made in the details disclosed without departing from the spirit of the invention, as expressed in the following claims.

I claim:

1. An apparatus of the character described, comprising a mast mounted to turn about its long axis, means forming the only support for the mast and arranged at the lower end portion thereof, the mast being rotatable for an entire revolution on said supporting means an arm having an inner end pivotally connected to the upper end portion of the mast, load-lifting means connected to the outer end of the arm, and a hy-

draulic ram connecting a medial portion of the mast to a medial portion of the arm.

2. An apparatus of the character described, comprising a mast mounted to turn about its long axis, means forming the only support for the mast and arranged at the lower end portion thereof, the mast being rotatable for an entire revolution on said supporting means an arm having an inner end pivotally connected to the upper end portion of the mast, the inner end of the arm being adjustably connected to the mast to permit said end to be raised or lowered, load-lifting means connected to the outer end of the arm, and a hydraulic ram connecting a medial portion of the mast to a medial portion of the arm.

3. An apparatus of the character described, comprising a mast mounted to turn about its long axis, means forming the only support for the mast and arranged at the lower end portion thereof, the mast being rotatable for an entire revolution on said supporting means an arm having an inner end pivotally connected to the upper end portion of the mast, load-lifting means connected to the outer end of the arm, and a hydraulic ram connecting a medial portion of the mast to a medial portion of the arm, the ram being adjustably connected to the arm so that its upper end may be secured to the arm at various points along the length thereof.

4. An apparatus of the character described, comprising a hollow pedestal arranged at a slight angle to the vertical, a mast having its lower end portion rotatably mounted in the pedestal for a turning movement of 360°, an arm having an inner end pivotally connected to the upper end portion of the mast, load-lifting means suspended from the outer end of the arm, and a hydraulic ram connecting a medial portion of the mast to a medial portion of the arm.

5. An apparatus of the character described, composing a hollow pedestal arranged at a slight angle to the vertical and adapted to be mounted on a vehicle, a mast arranged at the same angle to the vertical and having its lower end portion rotatably mounted in the pedestal, an arm having an inner end pivotally connected

to the upper end portion of the mast, load-lifting means suspended from the outer end of the arm, a piston rod having an upper end pivotally connected to a medial portion of the arm, a cylinder pivotally connected to a medial portion of the mast, a plunger on the rod operating within the cylinder, and controllable means for introducing a liquid into and discharging a liquid from the lower end portion of the cylinder.

6. An apparatus of the character described comprising a hollow pedestal arranged at a slight angle to the vertical and adapted to be mounted on a vehicle, a mast member arranged at the same angle to the vertical and having its lower end portion rotatably mounted in the pedestal, an arm member having an inner end pivotally connected to the upper end portion of the mast member, load-lifting means suspended from the outer end of the arm member, a piston rod having an end pivotally connected to a medial portion of one of said members, a cylinder pivotally connected to a medial portion of the other member, a plunger on the rod operating within the cylinder, and controllable means for introducing a liquid into and discharging a liquid from the lower end portion of the cylinder for controlling relative movement of the plunger and cylinder.

10 15 20 25 30 35 40 45

7. An apparatus of the character described, comprising a pedestal arranged at a slight angle to the vertical and adapted to be mounted on a vehicle, a mast member arranged at the same angle to the vertical and having its lower end portion rotatably supported by the pedestal, an arm member having an inner end pivotally connected to the upper end portion of the mast member, load-lifting means suspended from the outer end of the arm member, a piston rod having an end pivotally connected to a medial portion of one of said members, a cylinder pivotally connected to a medial portion of the other member, a plunger on the rod operating within the cylinder, and controllable means for introducing a liquid into and discharging a liquid from the lower end portion of the cylinder for controlling relative movement of the plunger and cylinder.

PHILIP W. SOUCIA.
